United States Patent Office

Des. 195,643
Patented July 9, 1963

195,643

STAMP VENDING MACHINE

Lloyd J. Andres, Miami, Fla., assignor to American Sumatra Tobacco Corporation, East Hartford, Conn., a corporation of Delaware

Filed Mar. 9, 1962, Ser. No. 69,165

Term of patent 14 years

(Cl. D52—3)

FIG. 1

FIG. 2

FIG. 3

FIG. 1 is a perspective view of a stamp vending machine, showing my new design.

FIG. 2 is a fragmentary cross-sectional view taken through the section line 2—2, FIG. 1.

FIG. 3 is a fragmentary cross-sectional view taken through section line 3—3, FIG. 1.

The broken lines showing stamps are for illustrative purposes only.

The dominant features of the design are shown in full lines.

I claim:

The ornamental design for a stamp vending machine, as shown and described.
